CIRCULAR RADIO TUNING FREQUENCY CONTROL WITH TRANSVERSE INDICATOR FACES

Maurice D. Katz, 35 Broadway,
Lawrence, N.Y. 11559

Filed Mar. 12, 1971, Ser. No. 123,938

Term of patent 14 years

Int. Cl. D14—03, 99

U.S. Cl. D26—1

FIG.1

FIG.2

FIG. 1 is a front perspective view of a circular radio tuning frequency control with transverse indicator faces showing my new design; and

FIG. 2 is a perspective view of the control installed in a radio, the indicia has been omitted from the control for ease of illustration.

The broken lines representing the radio is shown for illustrative purposes only.

I claim:

The ornamental design for a circular radio tuning frequency control with transverse indicator faces, substantially as shown and described.
